UNITED STATES PATENT OFFICE.

LAWRENCE R. BLACKMORE, GEORGE C. BLACKMORE, AND JOSEPH J. BLACKMORE, OF NEWARK, NEW JERSEY.

DESIGN FOR A HORIZONTAL RADIATOR.

SPECIFICATION forming part of Design No. 20,254, dated November 4, 1890.

Application filed September 9, 1890. Serial No. 364,489. Term of patent 7 years.

To all whom it may concern:

Be it known that we, LAWRENCE R. BLACKMORE and GEORGE C. BLACKMORE, citizens of the United States, and JOSEPH J. BLACKMORE, a subject of the Queen of Great Britain, all residing at Newark, Essex county, New Jersey, have invented a certain new and useful Design for Horizontal Radiators, fully described and represented in the following specification and the accompanying drawing, forming a part of the same.

This design relates to the ornamentation of radiators composed of horizontal sections or loops, and is specially applicable to radiator-sections having rounded ends.

The essential feature of the design consists in vertical columns of ornamentation upon the surface of the radiator composed of series of similar patterns upon adjacent portions of the sections, the same resting upon a horizontal base consisting in an ornamental pattern extending across the foot of the radiator.

The design is illustrated in the annexed drawing, in which *a a* are the radiator-sec-

tions having similar ornamental patterns *b* upon their ends, and thus adjacent to each other, the several patterns presenting in conjunction with one another vertical columns of ornamentation at the ends of the radiator. The foot of the radiator is provided with an ornamental pattern *c*, extending across the same, which presents the appearance of a base supporting the columns *b* of ornamentation.

Having thus set forth the nature of the design, what we claim herein is—

The design for a radiator herein shown and described.

In testimony whereof we have hereunto set our hands in the presence of two subscribing witnesses.

LAWRENCE R. BLACKMORE.
GEORGE C. BLACKMORE.
JOSEPH J. BLACKMORE.
